UNITED STATES PATENT OFFICE.

ELMER L. SCHUMACHER, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

1,265,531.

Specification of Letters Patent. Patented May 7, 1918.

Application filed November 30, 1917. Serial No. 204,646.

To all whom it may concern:

Be it known that I, ELMER L. SCHUMACHER, a citizen of the United States, residing at Southbridge, in the county of 5 Worcester and State of Massachusetts, have invented certain new and useful Improvements in Ophthalmic Mountings, of which the following is a specification.

This invention relates to improvements in 10 ophthalmic mountings and has particular reference to an improved construction of frame member.

One of the leading objects of the present 15 invention is the provision of a novel and improved mounting of the well known Windsor type, having an inner metallic and an outer non-metallic portion.

A further object of the present invention is the provision in a mounting of this type, 20 of novel and improved means for readily but securely connecting the said metallic and non-metallic parts to provide a firm and unitary construction therefrom.

A further object of the present invention 25 is the provision of a novel and improved structure of this character in which much lighter weight non-metallic material may be employed than has hitherto been possible, and which will consequently present a more 30 neat and desirable appearance and one less conspicuous when on the face of the wearer than do similar mountings of this general type at the present time.

Other objects and advantages of my invention 35 proved construction should be readily apparent by reference to the following specification taken in connection with the accompanying drawings, and it will be understood that I may make any modifications in the 40 specific details of construction shown and described within the scope of the appended claims without departing from or exceeding the spirit of my invention.

Figure I represents a front elevation of a 45 mounting embodying my improvements.

Fig. II represents an enlarged fragmentary sectional view illustrating the manner of connecting the frame ends together.

Fig. III represents a view of the outer 50 frame member and attaching device carried thereby.

Fig. IV represents a sectional view of a slightly modified form of invention.

Fig. V is a similar view illustrating a slightly different connecting member. 55

Fig. VI is a sectional view of a connecting member by which the parts may be more securely drawn together.

Fig. VII is a sectional view of a slightly modified arrangement of the parts shown in 60 Fig. II.

Fig. VIII is a view of another method of attachment.

Fig. IX represents a form of my invention 65 in which the attaching devices are concealed.

Fig. X is an illustration of the use of an encircling band.

Fig. XI is a sectional view of a further 70 modification.

In the drawings, in which similar characters of reference are employed to denote corresponding parts throughout the several views, the numeral 1 designates the bridge or lens connecting member, while carried 75 by the ends of the bridge are the metallic frame members 2 adapted to receive in their grooves 3 the usual lenses 4, and having extending outwardly therefrom the joint plates or end pieces 5 which are preferably suitably drawn together, as for example by the screws 6, to connect the frames but allow of their separation when desired to insert or remove a lens from the groove 3. 80

I am aware that previous to my invention 85 certain frames have been constructed in which the inner metallic frame has had formed or secured therearound a non-metallic frame of ornamental character, preferably formed from shell, zylonite or the like, but in the form of construction hitherto employed, use has been made of a screw or similar fastening device, requiring a relatively large and heavy appearing outer frame member. 95

One of the principal objects of my present invention, therefore, is the provision of a fastening device of improved construction which may be readily applied, which may positively and securely connect and unite 100 the parts, and which will be capable of use either with the heavy frames or rims now commonly employed, or with extremely thin and light rims, as may be preferred, and which will prove equally efficient in either 105 event.

In the carrying out of this purpose in the form of my invention illustrated in Figs. II and III, I have shown as surrounding the frame 2 the non-metallic band or rim 8, while forced inward through the rim 8 is the wire or similar fastening device 9 piercing the frame a short distance from its end and formed with a slight head 10 to prevent its pulling through the rim. This fastening device after being passed through is bent down against the inner face of the rim and so embedded in the rim itself that the rim may lie flush against the frame member 2 and the wire 9 will just contact with the outer face of this frame member.

It will be noted by reference to Fig. II that the wire or fastening device projects beyond the end of the rim 8 and has its opposite end received and bent down into the recess as at 11 in the joint plate 5. The strength of the member 9 is such that it will normally securely hold the parts together when the frame is open, although permitting of bending of its end out of the recess if desired for any reason to remove the non-metallic band, while when the frame is secured around a lens the parallel portions of the two fastening devices 9 will abut each other and the clamping together of the plates 5 will securely lock the parts 9 against any withdrawing movement.

It is to be noted that the plates 5 are provided with the apertures 12 through which the fastening devices 9 pass.

In Fig. IV, I have shown an alternative form of my construction in which the member 9 extends outward from the plate 5 and has its end forced into and clenched over as at 13 in the rim 8 to securely connect the parts.

Another modified form is shown in Fig. V, in which the member 9 is forced through the rim 8 and passed through the aperture 12 in the joint 5, but in place of being formed with the head 10 is bent into the hook 14 which is then pressed to embed it within the frame. In this form there is, therefore, no projecting head or the like to disturb the continuous curve of the outer face of the rim, and at the same time the parts are securely interlocked.

Fig. VI illustrates another modified form of my invention in which the member 9 in place of being bent over against the plate 5 has its end threaded as at 15 to receive the nut 16 which may be tightened up to tightly and firmly draw the end of the rim 8 against the plate 5.

Fig. VII illustrates a reversal of the parts shown in Fig. II, in that the head 10 is placed on the inner side of the rim member 8 and the fastening device 9 comes outwardly therefrom and then is extended along the outer face of the rim 8 in place of the inner face being then similarly passed

through the aperture 12 in the plate 5 and clenched down against the inner face of the plate.

Fig. VIII shows a modification in which a plain rivet 17 is used to connect the parts. 70

Another illustration is that of Fig. IX, in which the prongs 18 are shown as pressed outward from the center of the frame 2, these prongs being employed either alone or in conjunction with a locking pin 19. 75 This is very desirable in that the fastening devices are invisible and are capable of easy application, in that the rim member may be pressed over the prongs 18 when the frame is opened or partially straightened out, and as the frame is bent up again into round form to join the plates 5 the bending will serve to tighten the engagement between the prongs and frame member and cause most secure and tight interlocking of the parts, although permitting of ready disengagement when they are again widely opened. 80

In Fig. X, I have shown an encircling band 20 as connecting the parts. 90

In Fig. XI, I have illustrated a slight modification of the construction shown in Fig. VII, in which the end of the staple or fastening device 9 in place of lying entirely within the recess in the inner face of the end piece, has an extension 21 projecting inwardly of the frame member and adapted to be received in a recess 22 in the edge of the lens, the end of the staple thus interlocking with the lens and preventing rotative movement of the lens within the frame. 100

It will be understood that while I have illustrated a particular fastening device in Fig. XI, having the inwardly projecting portion to engage and lock the lens, I might similarly employ the inner end of the rivet 17, a projecting portion of the locking pin 19, or other fastening device for this purpose without in anywise departing from or exceeding the spirit of my invention, it being thought necessary, however, for personal understanding of the invention, to explain but one form of my invention with the locking extension as shown and claimed. 115

I claim:

1. In a device of the character described, the combination with a non-metallic rim member and an abutment plate, of a staple carried by one of said parts and securely interlocking with the other of the parts for retaining them in engagement one with the other. 120
2. In a device of the character described, the combination with a non-metallic rim member, of a staple embedded therein and projecting therefrom, and an abutment plate to which the projecting portion of the staple is secured. 125
3. In a device of the character described, 130

the combination with a lens frame having abutment plates projecting therefrom, of a supplemental rim encircling the frame, and staples having interlocking engagement with the rim and with the abutment plates for securing the parts together.

5. In a device of the character described, the combination with a lens frame, of a supplemental rim encircling the frame, plates carried by the frame and abutting the ends of the rim, and staples embedded in the rim and clenched against the plates to securely connect the parts.

10. In a device of the character described, the combination with a lens frame having projecting portions, of a rim encircling the frame and abutting the projecting portions, and means engaging the projections and an exterior portion of the rim for drawing the 15 rim securely against the frame and its projections.

15. In a device of the character described, the combination with a frame having connecting plates projecting therefrom, of a rim 20 encircling the frame and having its ends abutting the plates, staples embedded in and

projecting from the rim, the plates having apertures to receive the staples, and the projecting portions of the staples extending through the apertures and being clenched 30 against the plates to securely connect the parts, substantially as illustrated.

25. In an ophthalmic mounting, the combination with a metallic frame, of a notched lens within the frame, a non-metallic frame, 35 and a fastening device connecting the metallic and non-metallic frames and having a portion projecting inwardly to engage the notch of the lens and lock the lens against rotation within the frames.

30. In a device of the character described, a metallic holding member, a non-metallic member, and a staple carried by one of said parts and securely interlocking with the other of the parts for retaining them in engagement one with the other.

35. In testimony whereof I have affixed my signature, in presence of two witnesses.

ELMER L. SCHUMACHER.
